MARDER, LUSE & CO.
CHICAGO.

UNITED STATES PATENT OFFICE.

CARL MÜLLER, OF CHICAGO, ILLINOIS, ASSIGNOR TO MARDER, LUSE & CO., OF SAME PLACE.

DESIGN FOR A FONT OF PRINTING-TYPE.

SPECIFICATION forming part of Design No. 12,796, dated February 28, 1882.

Application filed November 18, 1881. Term of patent 7 years.

To all whom it may concern:

Be it known that I, CARL MÜLLER, of Chicago, in the county of Cook and State of Illinois, have invented a new and useful Design for 5 a Font of Printing-Type, which I have named "Mentor;" and I do hereby declare that the following is a full, clear, and exact description of the invention, which will enable others skilled in the art to which it appertains to make and 10 use the same, reference being had to the accompanying printed specimens, which form a part of this specification.

My new design for a font of printing-type consists of a heavy-face letter, of medium 15 width, shaded on the right side and on the bottom with a fine shade-line, and having the central portion of the ceriphs of the letters nicked in a triangular shape, as clearly shown in the printed specimens of the type.

What I claim as new, and desire to secure by 20 Letters Patent, is—

The new design for a font of printing-type, consisting of a heavy-face letter of medium width, shaded on the right side and on the bottom with a fine shade-line, and having the central portion of the ceriphs of the letters nicked 25 in a triangular shape, substantially as described, and as shown in the printed specimens.

In testimony that I claim the foregoing as my own invention I affix my signature in presence of two witnesses.

CARL MÜLLER.

Witnesses:

JOHN MARDER,
A. P. LUSE.
